UNITED STATES PATENT OFFICE.

JOHN E. HARE, OF CHICAGO, ILLINOIS.

FLASH-LIGHT APPARATUS.

No. 874,403.

Specification of Letters Patent.

Patented Dec. 24, 1907.

Application filed January 7, 1907. Serial No. 351,269.

To all whom it may concern:

Be it known that I, JOHN E. HARE, a citizen of the United States, residing at Chicago, in the county of Cook and State of Illinois, have invented certain new and useful Improvements in Flash-Light Apparatus, of which the following is a specification, reference being had to the accompanying drawings.

10 My invention relates to photographic apparatus, and has particularly for its object to provide a new and improved apparatus for use in taking flashlight photographs.

As is well known, the use of flashlight powder has heretofore been attended with considerable risk to the operator, and, moreover, the apparatus heretofore employed has not been arranged to throw the light upon the subject to be photographed, but, on the contrary, to direct it upward regardless of the position of the subject to be photographed.

20 My improved apparatus, by which the objections above noted are avoided and various other advantages secured, consists in providing an improved holder having means for supporting and igniting flashlight powder contained in a sealed cartridge or envelop. This cartridge is arranged so that it may be put in place and ignited without being 30 opened, so that at no time is the powder exposed.

25 A further feature consists in so arranging the holder that the flash may be directed immediately upon the subject to be photographed, so that the full benefit of the flash is secured.

35 A still further important feature of my invention is that the holder is at all times between the operator and the cartridge, so that it affords a complete shield and insures his protection against injury from the ignition of the powder.

40 In addition to these more generic features of improvement my invention includes the provision of means by which the powder may readily be ignited, and of safety means by which accidental ignition of the powder may be guarded against, as well as other features which will appear in the following specification.

50 In the accompanying drawings,—Figure 1 is a perspective view of my improved holder, showing the cartridge in place, some parts being broken away; Fig. 2 is a section on

line 2—2 of Fig. 1; Fig. 3 is a vertical section 55 of the upper portion of the handle, showing the connections for closing the circuit through the fuse by which the flash powder is ignited; Fig. 4 is an under-side view of the parts shown in Fig. 3; Fig. 5 is a substantially central vertical section of the apparatus; Fig. 6 is a front view of the cartridge, part of the paper envelop being broken away; Fig. 7 is a vertical section on line 7—7 of Fig. 6; Fig. 8 is a detail view of a part of the cartridge, showing the fuse; and Fig. 9 is a partial vertical section on line 9—9 of Fig. 8.

Referring to the drawings,—10 indicates a board or plate of wood, or other suitable material, normally in an upright position, although, as will hereinafter appear, it may be turned to any desired position. Said plate is provided at the lower portion of its rear side with a box or case 11, as shown in Fig. 1, said case being designed to hold a suitable 75 electric battery 12 by which the fuse is burned out, as will hereinafter appear.

13 indicates a handle, which is preferably upright, as shown in Fig. 1, and is connected at its lower end with the case 11 and at its 80 upper end with the upper portion of the plate 10 by means of a bracket 14. The form and arrangement of the handle may, of course, be varied, as the details thereof are not essential.

15 indicates a push-button carried by the handle, preferably in the upper end thereof, as shown in Figs. 1 and 3, and normally held pressed upward by a spring 16,—the latter being mounted in a block of suitable non-conducting material 17.

18 indicates a pin within the spring 16 and at its upper end connected with the push-button 15, as shown in Fig. 3. The lower end of the pin 18 is normally above and a 95 short distance from two contact plates 19—20, respectively, secured to the block 17 and connected by wires 21—22. One of the wires 21 is connected with one of the terminals of the battery 12,—the other wire 22 being connected with one of two metallic plates 23—24 secured on the front side of the plate or board 10 near the central portion of the lower edge thereof, as shown in Figs. 2 and 6. As shown, said plates 23—24 are secured to 100 the board or plate 10 a short distance apart and are provided with up-turned lips so that the cartridge hereinafter described may be

slipped down into engagement therewith. In other words, said plates 23—24 form clips which receive and support the lower edge of the cartridge and also make electrical contact therewith, as will hereinafter appear. As has been explained, one of said plates 23 is connected with the contact plate 20 by means of the wire 22. The other plate 24 is connected by a wire 25 with the pivot 26 of a 10 switch 27.

28 indicates a contact point adapted to be engaged by the switch 27 and connected by a wire 29 with the other terminal of the battery 12. It will thus be seen that when the 15 switch 27 is in engagement with the contact point 28 and the push-button 15 is depressed so as to connect plates 19—20 by means of the pin 18, the plates 23—24 are connected, respectively, with the opposite terminals of the 20 battery, and by connecting them the circuit may be closed.

30 indicates the cartridge, consisting in its most improved form of a flat board or piece of cardboard having at its lower edge a longitudinal corrugation 31 with which connect a series of vertical corrugations 32, as shown in Fig. 6. Stretched over one face of the cardboard is a sheet of tissue paper 33, or other suitable material, which is secured at 25 its edges to the cardboard so that the sheet lies closely thereover. The tissue paper, or other envelop, is to hold the flash powder upon the cardboard, and the corrugations serve to hold the powder distributed over the 30 cardboard so that it does not run together or accumulate in a mass.

At one edge of the cardboard, and near the center thereof in position to register with the plates 23—24, are provided two contact 40 plates 34—35, preferably formed of clips, which embrace the lower margin of the cardboard, as shown in Fig. 9. At the front side of the cardboard—*i. e.* the side which is outermost or away from the plate 10—the 45 plates 34—35 are connected by a piece of platinum wire, or other suitable fuse, 36, as shown in Figs. 6, 8 and 9. The arrangement is such that the clips or plates 34—35 fit tightly between the plates or clips 23—24, respectively, the fuse 36 being on the outside. The powder being also on the outer 50 surface of the cartridge, it will be evident that the fuse is enveloped by the flash powder lying in the horizontal or lower corrugation 31, and as it serves as a means of electrical connection between the plates 23—24, when the circuit is closed by depressing the push-button 15,—the switch 27 having been 55 previously closed,—the current from the battery 12 passes through said fuse, burning it out, and consequently setting off the cartridge. For securing the upper portion of the cartridge in place, a spring clip 37 is provided at the upper part of the holder, as shown in 60 Figs. 1, 5 and 6.

The use of the apparatus will be readily understood from the foregoing description, but by way of recapitulation it will be explained that when a photograph is taken the operator places a cartridge in the holder, 70 fitting its clips or contact plates 34—35 in engagement with the plates 23—24 and securing its upper edge by the clip 37, so that the cartridge is held closely against the flat surface of the holder 10. At this time the 75 safety switch 27 is preferably open, so that the powder will not be set off even if the push-button 15 is accidentally depressed. When the cartridge has been put in place, the safety switch 27 is closed and the operator so holds the holder that the cartridge is directed toward the subject to be photographed, and this may readily be done regardless of the position of the subject, as the 80 holder may be turned up or down, or to one 85 side or another, with entire freedom. When the picture is to be taken, the operator simply depresses the push-button, thereby closing the circuit through the fuse, which thereby at once ignites the flash powder. 90

It will be seen that the operator is at all times perfectly protected, and, moreover, the flash powder also is completely protected, so that the operation of the apparatus is not interfered with by wind, by agitation of the holder, or by any other cause 95 which does not rupture the cartridge. Moreover, by putting up the flash powder in cartridges as described it may be very conveniently handled before it is placed in the 100 holder, and the operator may readily equip himself with any desired number of cartridges. By means of my improved apparatus, therefore, the operation of taking flashlight photographs is greatly simplified. 105

It will be understood that the various parts of the apparatus may be made of any suitable materials, although for the cartridge I prefer a cardboard base with a tissue paper envelop or cover, as the cardboard may 110 readily be corrugated and is cheap, and the tissue paper does not interfere with the light caused by the ignition of the flash powder; also the character of the fuse may be varied,—the term “fuse” being employed in the 115 claims generically to indicate the device which acts immediately to ignite the powder, whether the fuse be a fuse strictly speaking, or some other equivalent device.

That which I claim as my invention and 120 desire to secure by Letters Patent is,—

1. A flashlight apparatus, comprising a vertically-disposed plate having means for supporting a cartridge at one side thereof, said plate having electric contacts adapted to engage corresponding contacts carried by the cartridge when the cartridge is in position on the plate, and means carried by the plate for closing the circuit through said contacts after the cartridge is in position. 125 130

2. A flashlight apparatus, comprising a vertically-disposed plate having means for supporting a cartridge at one side thereof, said plate having electric contacts adapted to engage corresponding contacts carried by the cartridge when the cartridge is in position on the plate, and a switch carried by the plate for closing the circuit through said contacts after the cartridge is in position, and an auxiliary safety switch for preventing accidental closing of the circuit through the cartridge. 30
5. A flashlight apparatus, comprising a plate, means at one side thereof adapted to engage the edges of a flat cartridge to secure said cartridge at one side of said plate, contacts carried by said plate and adapted to engage corresponding contacts carried by the cartridge, a handle at the opposite side of said plate, and means for closing the circuit 35 through the cartridge. 40
3. A flashlight apparatus, comprising a plate having means for securing a cartridge at one side thereof, a handle at the opposite 15 side thereof, contacts carried by the plate and adapted to engage corresponding contacts carried by the cartridge for making electrical connection therewith, and a switch carried by the handle for closing the circuit 20 through the cartridge. 45
4. A flashlight apparatus, comprising a plate having means for securing a cartridge at one side thereof, a handle at the opposite side thereof, contacts carried by the plate 25 and adapted to engage corresponding contacts carried by the cartridge for making electrical connection therewith, a switch carried by the handle for closing the circuit through the cartridge, and a safety switch 50

carried by the plate for preventing accidental closing of the circuit through the cartridge. 30

5. A flashlight apparatus, comprising a plate, means at one side thereof adapted to engage the edges of a flat cartridge to secure 35 said cartridge at one side of said plate, contacts carried by said plate and adapted to engage corresponding contacts carried by the cartridge, a handle at the opposite side of said plate, and means for closing the circuit 40 through the cartridge. 45

6. A flashlight cartridge, comprising a flat board having a tissue paper envelop for confining the flash-powder upon the board, said board having a fuse embedded in the flash- 45 powder, and contacts adapted to engage corresponding contacts on a suitable holder. 50

7. A flashlight cartridge, comprising a flat board having corrugations and having a tissue paper envelop for confining the flash- 50 powder upon the board, said board having a fuse embedded in the flash-powder, and contacts adapted to engage corresponding contacts on a suitable holder.
